ATTORNEY.

UNITED STATES PATENT OFFICE.

LEO M. HARVEY, OF LOS ANGELES, CALIFORNIA.

VEHICLE-WINDOW.

1,357,167.

Specification of Letters Patent. Patented Oct. 26, 1920.

Application filed June 16, 1919. Serial No. 304,591.

To all whom it may concern:

Be it known that I, LEO M. HARVEY, a citizen of the United States, residing at the city of Los Angeles, county of Los Angeles, State of California, have invented new and useful Improvements in Vehicle-Windows, of which the following is a specification.

My invention primarily relates to an auto top and consists in the peculiar construction of the metal frame which surrounds the glass of the window, and its manner of attachment to the material which forms the top of the vehicle.

In the drawings forming a part of this application Figure 1 shows a fragment of the top of the vehicle viewed from the inside. Fig. 2 is a section on the line 2—2 of Fig. 1. Fig. 3 is an enlarged edge view of a fragment of lining of the two members of the frame. Fig. 4 is a section on the line 4—4 of Fig. 3. Fig. 5 is an enlarged detail.

Referring to the drawings, 10 is the outer member of the top of the vehicle and 11 is the lining thereof. My improved frame 25 consists of an outer member 12 of sheet metal which is stamped out and pressed to the desired shape. The edges of member 12 are turned over and hold a sheet metal plate or strip 13 which for distinction will be 30 called the lining. In this lining are punched holes 14 and the metal is pressed outwardly and threaded for the reception screw 15. The inner member 16 of the frame consists of sheet metal which is stamped out and 35 pressed to the desired shape. The edges of member 16 are turned over and hold a sheet metal plate or strip 17 which for distinction will be called the lining. In lining 17 are punched holes 18 and the metal is pressed 40 outwardly and forms around the hole a ledge 20 which is preferably higher at one side than at the other, thereby forming a lock in the nature of a lock washer to hold screws 15 from accidentally turning when 45 the parts are assembled. In the outer edges of linings 13 and 17 are small sections which are deformed by being pressed alternately outwardly and inwardly to form lugs 21 as best shown in Fig. 3. These lugs are so 50 formed that an inwardly projecting lug of lining 13 registers with an outwardly projecting lug of lining 17 and the adjacent outwardly projecting lugs of lining 13 register with the inwardly projecting lugs of lining 55 17. Holes 22 are provided in member 16 for the passage therethrough of screws 15.

In assembling a hole would be cut in the material of the top so that the inner edge would register with the inner edge of the frame and holes would be punched in such material to register with the screw holes of the inner member. The inner member of the frame would be positioned and held in place by screws placed in the inner member. The glass pane 23 would then be positioned. The outer member of the frame would then be secured by the screws. To save metal I make the lining members of the frame in two parts and of sheet steel. The outer parts of the frame may be very light and of any desired metal that will present a neat and attractive appearance as the strain all comes on the lining members. These lining members could be cast, but stamping is cheaper and better.

By this construction a neat, cheap, and durable frame is provided. Other means may be used to connect the members of the frame as small bolts not shown.

Having described my invention I claim. 80
1. A metal window frame for vehicles comprising an outer and an inner member each having a lining, said lining having lugs along the outer edges, said lugs alternately projecting in opposite directions; and means to connect said members.

2. A metal window frame for vehicles comprising an outer and an inner member each having a lining, said linings having holes therein with the portions surrounding said holes pressed outwardly, the holes in the lining of the outer member being threaded and the projecting portions of the lining of the inner member being formed to produce a lock-washer effect, and screws adapted to connect said members.

3. A metal window frame for vehicles comprising an outer and an inner member each having a lining, said linings having lugs around the outer edges projecting alternately in opposite directions and having holes therein, the holes of the lining of the outer member being threaded, and the holes of the lining of the inner member having lock washer ledges; and screws adapted to connect said members.

In witness that I claim the foregoing I have hereunto subscribed my name this 11th day of June, 1919.

LEO M. HARVEY.
